UNITED STATES PATENT OFFICE.

CHARLES F. H. BOHNHARDT, OF LONG BEACH, CALIFORNIA, ASSIGNOR OF ONE-HALF
TO JOSEPH R. BARIL, OF LONG BEACH, CALIFORNIA.

FLOATING ROOF AND SEALING MEANS THEREFOR.

Application filed August 20, 1925. Serial No. 51,371.

My present invention being referred to as a floating roof and sealing means therefor, it may be understood to be an object of this invention to provide tanks, such as oil or gas tanks, with roofs which are adapted to move up and down within a circular enclosing wall; and a preferred embodiment of my invention may comprise a substantially circular horizontal roof section terminating peripherally in a cylindrical element constituting an inner wall of an annular pocket adapted to contain water or another liquid, the outer wall of this pocket being spaced but slightly from the outside wall of the tank, and said annular pocket being adapted to receive also a plurality of telescopically interfitting cylindrical bands respectively provided with interfitting terminal portions constituting means for holding the same in their intended concentric and overlapping relationship during the rise and fall of said central roof section and substantially preventing the entrance of air or the escape of the confined fluid regardless of the elevation or depression of said central roof section.

To allow for escape and entrance of air as the tanks are filled and emptied, and allow for expansion and contraction of the contents with changes in temperature, tanks currently used in the storage of gasoline, or the like, are commonly left open to the air; but this results not only in the accumulation of explosive gaseous mixtures in the spaces above oil levels, but in extensive losses by evaporation; and it is an object of this invention substantially to avoid the risks and losses incidental to this described current construction.

It is an object of this invention to provide an oil tank, or the like, with a movable roof so supported as to avoid any large space for the accumulation of gases, and a preferred embodiment of my invention may comprise a roof adapted to rest directly upon the top of a body of liquid, rising and falling with the expansion and contraction or increase and diminution thereof.

It is a further object of my invention to provide a tank comprising an ordinary cylindrical shell with a roof adapted to rise substantially to the top thereof or to descend, and a preferred embodiment of this invention may comprise a tank having vertical interior guides and a floating roof provided with a circumferential trough for a

sealing liquid and with rollers adjustably disposed therebelow, this trough housing telescopically interfitting sections respectively provided with subsidiary liquid-seal troughs; and preferred embodiments of my invention may comprise a truss system external to the mentioned roof, and struts extending therefrom toward the lower edge of said circumferential trough, and optionally also supplemental supports adapted to aid in carrying the weight of the roof whenever a tank is completely empty or is drained down to a low level.

Other objects of my invention may be best understood from the following description of an advantageous embodiment thereof, taken in connection with the appended claims and the accompanying drawings, in which

Fig. 1 is a partial top plan view.

Fig. 2 may be regarded as a vertical half-section, with parts broken away, taken substantially as indicated by the line 2—2 of Fig. 1, and showing my floating roof as occupying its elevated position.

Fig. 3 is a view comparable to the right hand portion of Fig. 2, but showing the roof as in a partially lowered position.

Fig. 4 is a fragmentary horizontal section, taken substantially as indicated by the line 4—4 of Fig. 2.

Fig. 5 is a detail view showing an optional construction especially suitable for use in preventing the sealing liquid from being blown out as a result of interior gas pressure.

Referring to the details of that specific embodiment of my invention shown in Figs. 1 to 4 inclusive, 11 may be the outer shell or main wall of a substantially circular tank designed for the storage of a combustible fluid, or the like, and 12 may be the substantially horizontal closure plate of a floating roof, which may be strengthened by exterior and overlying trusses, shown as comprising I-beams 13, uprights 14 and tension members 15, and may be surrounded by a liquid-seal trough 16, comprising vertical cylindrical bands 17 and 18 connected at their bottom edges by a horizontal band or plate 19, but spaced apart sufficiently to receive telescopically interfitting subsidiary sections 20, 21, 22 and 23, the first of these being shown rigidly secured at its lower edge to the plate 19, and the last as rigidly secured at its upper edge, by means comprising 110

2
a horizontal plate 23', to the upper edge of the main wall or outer shell 11.

A circular opening 36, provided with a tightly closable cover 37, may be located at 5 or near the center of our floating roof; subsidiary legs 38 may be secured at any appropriate intervals therebelow, to support the roof from the bottom 24 when the tank is empty; angle members 24', or their equivalent, may be used as required for reinforcement; and means such as struts 25, shown as extending between plate 12 and oppositely disposed channel elements 26, secured to the plate 19 and carrying rollers 15 27, may contribute to the rigidity of the entire floating roof organization,—rollers 27 being preferably grooved, as at 28, to interfit with substantially vertical rails 29, which may be secured by additional sections of 20 channel bar 24' and may contribute to the rigidity of the tank, whether or not the bottom is slightly wider than the top, as shown. The wheels 27 may be adjustable by means such as nuts 30, on a threaded rod 25 31, projecting from a yoke 32.

The main peripheral trough 16 being normally kept filled with a sealing liquid, which may be water, and the respective top and bottom edges of the subsidiary sections 20, 30 23, being oppositely rebent, as at 33 and 34, in such manner as to form subsidiary seals 35 (see Fig. 3) it will be obvious that my floating roof may rise and fall without loss of seal. Oil, or the like, may be delivered into the tank by valved pipes (not shown); and as soon as the level of this introduced oil shall reach the plate 12, the cover 31 on a manhole 36 may be tightly closed; so that the entire roof must float up 40 with the rise of the oil, no appreciable space being left for the accumulation of explosive gases.

Even if the cover 37 is not tightly closed, the concavity provided by the plate 12 and the vertical elements 17 and 36, said vertical elements being shown as carried above the level of said plate, may be compared with the hull of a non-sinkable boat, tending to rise with the oil level; and I may obtain 45 substantially all of the advantages of my invention, as used for the storage of oil, even if I provide "breather" openings, of a known type, as at B and B'; but when gases are to be stored in my tanks, it will be obvious that no such openings are intended to 50 be provided; and, whenever the interior pressures are such that the sealing liquid is liable to be disturbed by escaping gases or vapors, I may prefer to employ subsidiary sealing members of the types shown 55 in Fig. 5 as comprising rebent rims 33' and 34',—the former having associated therewith an upstanding flange 35' of sufficient height to provide a pocket so deep that the 60 sealing liquid is in no danger of being car-

ried above its upper edge by an outward rush of gas or vapor.

Rain water falling on the roof of a tank equipped and closed in the manner described can ordinarily do no harm, although it may 70 make up any deficiency in the sealing liquid, and may even be enabled to make its way into the interior of the tank—whose bottom is ordinarily required to be covered with water; but it may be noted that our invention 75 does permit a canvas or other cover or covers (not shown) to be supported above the tension members 15, or their equivalents, and/or over the entire tank for the exclusion of rain water or the sun's rays, 80 any appropriate additional supports (not shown) being provided as required therefor.

Although I have herein described a single complete embodiment of my invention, suggesting various alternative details, it 85 should be understood that various features of my invention may be independently employed; and also that numerous modifications might be devised by those skilled in the art, without the slightest departure from the 90 spirit and scope of my invention, as the same is indicated above and in the following claims.

I claim as my invention:

1. A tank and roof construction comprising 95 a main outer shell provided with guides therein; a roof vertically movable between said interior guides; and liquid seal means between said shell and said roof, said guides being engaged by rollers disposed below said liquid seal means.

2. A tank and roof construction comprising 100 a shell adapted to contain a fluid; a roof adapted to overlie and float upon the fluid so contained; sealing means therebetween comprising a major trough secured to said roof and adapted to contain telescopically 105 interfitting subsidiary shell elements, the outermost of said interfitting elements being rigidly secured to said shell.

3. A tank and roof construction comprising 110 a shell adapted to contain a fluid; a roof adapted to overlie and float upon the fluid so contained; sealing means therebetween comprising a major trough secured to 115 said roof and adapted to contain telescopically interfitting subsidiary shell elements respectively provided with oppositely rebent edges, the outermost of said interfitting elements being rigidly secured to said shell.

4. A tank and roof construction comprising 120 a shell adapted to contain a fluid; a roof adapted to overlie and float upon the fluid so contained; sealing means therebetween comprising a major trough secured to said roof 125 and adapted to contain telescopically interfitting subsidiary shell elements respectively provided with interfitting sealing means, the outermost of said interfitting elements being rigidly secured to said shell.

5. A tank roof comprising a substantially horizontal floating closure member adapted directly to overlie a contained liquid, a circumferential liquid seal trough extending 5 above and below the level of said roof and containing telescopically interfitting subsidiary shell elements adapted to extend between said trough and a main outer shell, the outermost of said interfitting elements 10 being rigidly secured to said shell.
6. A tank and roof construction comprising a main outer shell provided with guide rails therein; and a roof provided with rollers engaging said guide rails, said roof being 15 provided with a vertically expanding sealing element including a circumferential seal-
- ing trough, and said rollers being secured below said trough.
7. A tank and roof construction comprising a main outer shell provided with guide 20 rails therein; a roof provided with rollers engaging said guide rails, said roof being provided with a circumferential sealing trough, and said shell being provided with a downwardly extending expansible subsidiary 25 interior shell element secured at its upper edge to said main outer shell.

In testimony whereof, I have hereunto set my hand at Los Angeles, California, this 1st day of August 1925.

CHARLES F. H. BOHNHARDT.
